UNITED STATES PATENT OFFICE.

WILBER O. PLATT, OF OIL CITY, PENNSYLVANIA, ASSIGNOR TO JOSEPH REID GAS ENGINE COMPANY, OF OIL CITY, PENNSYLVANIA, A CORPORATION OF PENNSYLVANIA.

GOVERNOR.

1,121,201.

Specification of Letters Patent. Patented Dec. 15, 1914.

Application filed October 14, 1912. Serial No. 725,692.

To all whom it may concern:

Be it known that I, WILBER O. PLATT, a citizen of the United States, residing at Oil City, in the county of Venango and State of Pennsylvania, have invented certain new and useful Improvements in Governors, of which the following is a specification.

The object of my invention is to provide means whereby prompt and certain action of the operative parts can be obtained to control the speed of the engine and whereby fuel may be shut off at once from the engine when the belt becomes disengaged from its pulleys or broken; and with these and minor objects my invention consists of the parts and combination of parts as will be more fully hereinafter pointed out.

In the drawings, Figure 1 is a top plan view partly in section of a governor in normal position, embodying my invention. Fig. 2 is a detail view in elevation of the latch, its bigger and immediately associated parts, the parts being shown in normal position. Fig. 3 is a view similar to Fig. 1 with the parts in abnormal position. Fig. 4 is a view similar to Fig. 2 with the parts in abnormal position.

The reference character 1 designates the governor frame, 2 the governor balls, which may, generally speaking be of any approved construction.

The spindle consists of a lower portion 1^a and an upper portion 1^b abutting against each other. The lower portion, supporting the upper one is keyed in the frame 1 preferably by the screw 5^a which connects the pulley 5 with the governor frame 1, so as to revolve therewith, but also to slide axially in the governor frame actuated by the balls 2. The upper portion 1^b of the governor spindle is yoked as at 3, there being a bearing 4 extending across the yoke to be hereinafter referred to. The upper spindle portion 1^b is not keyed to, and does therefore not partake in the rotation of the frame 1. 5 is a governor belt pulley suitably mounted on the governor frame.

The bracket 6 is secured to the engine frame in any suitable manner and is pro-

vided with a suitable journal bearing 8 shown in section in Fig. 1, through which the spindle of the governor frame passes.

7 is an arm of bracket 6 having connection at one end with the enlargement which forms the bearing 8 of the governor frame, said frame being secured in said bearing by means of a set screw 9 engaging with a groove 1^c in the upper part of the frame.

A sleeve 10 extends at right angles from the arm 7 and is provided with an abutment screw plug 11, and a short arm 12 extending beyond said abutment on which one end of a coiled spring 13 is seated.

14 is a plunger slidably mounted and secured in the sleeve and projecting through openings formed in the arm 7 and brackets 6.

15 is a coiled spring one end of which is seated against the abutment plug 11 while the other end is seated against the bottom of the plunger 14. The plunger and its spring 15 are mounted in a hole formed in the sleeve.

16 is a bell crank lever pivoted in the yoked end 17 of the arm 7 by means of the pin 18. The upper arm of the bell crank lever is provided with a notch 19 at its outer end serving as a bearing which is constructed to bear on the bearing 4 of the spindle yoke 3 as clearly shown in the drawings.

It will be seen that the connection between these bearing points 19 and 4 is such that the connection between the two is especially adapted to be broken. This feature will be hereinafter referred to. The lower end of the bell crank lever 16 is connected to the spring 13, there being a seat or clamp 20, carried by the outer end of the spring adapted to be firmly secured to the said lever arm.

21 is a latch pivoted to the arm 7 of the bracket 6 as at 22 which is adapted to engage a notch 14^a in the plunger 14 to hold the plunger against the action of the spring 15. The latch is provided with a forwardly extending finger 23.

24 is a trigger pivotally mounted at 25 and constructed, when in normal position to engage the under face of the latch finger 23 when moved. It is desirable that there

be a slight distance between the under face of the finger 23 and the trigger, so that slight movements of the trigger will not be imparted to the latch. The outer end of the trigger is provided with a pin 26 on which is journaled an idler belt pulley 27 in alinement with the belt pulley 5 on the governor frame.

As will be seen in Fig. 1 the spring 13 normally holds the lever 16 on its bearings on the spindle yoke 3, against the action of the governor balls.

The pulley 27 rests on the inner face of the governor belt, thereby riding on the belt whereby the trigger is supported in the position shown in Figs. 1 and 2. If the governor belt should break, the pulley 27 drops down, throwing the opposite end of the trigger up, causing it to strike the latch, which is then thrown upward, thereby permitting the spring 15 to expand, which forces the plunger 14 outward against the bell crank lever 16, which raises the upper end of the lever from its bearing 4 in the spindle yoke 3, see Figs. 3 and 4. In this connection it will be noted that the upper end of the bell crank lever is not entirely withdrawn from the yoke on the end of the spindle, but stays in the yoke far enough to keep the yoke from revolving. The yoke would revolve if the lever was entirely withdrawn from the yoke and in that case it would not be as convenient to reset the latch and again put the governor in operation.

The spring 15 is much stronger than the spring 13 as will be understood from the operation above described, so that it can be compressed, as shown in Fig. 2, when the bell crank lever 16 is operated by the plunger 14.

A connection 28 extends from the arm of the bell crank lever to the fuel valves of the engine, so that as the bell crank lever is operated by the plunger 14 to raise it from the yoke 3, the connection 28 is moved to close the fuel valves. The spring 13 is strong enough to move the fuel valves one way, as will be understood.

I claim:

1. In a governor the combination with a governor yoke, of a pivotally mounted lever normally connected to the said yoke, a spring maintaining said normal connection, a plunger normally under tension constructed to move the lever relative to the governor yoke, a latch normally restraining said plunger, a trigger controlling said latch and holding it in normal position, and a pulley on the outer end of said trigger constructed to engage the governor belt, whereby when the said belt breaks the trigger is operated to release the latch whereupon the said plunger is free to move the lever from its normal position on the governor yoke.

2. In a governor for engines, the combination with the governor yoke, of a pivotally mounted lever, means normally holding said lever on said yoke against the action of the governor balls, a connection between said lever and the device to be controlled by the governor, a plunger normally under tension constructed to move said lever relative to the governor yoke, a latch normally restraining said plunger against movement, a trigger controlling said latch and holding it in normal position, and a pulley on the outer end of said trigger constructed to engage the governor belt, whereby when said belt breaks the trigger is operated to release the latch whereupon the plunger is free to move said lever from its normal position on the yoke and the fuel valves are closed.

3. In a governor the combination with the governor yoke, of a pivoted lever, a spring exerting pressure on said lever to hold said lever normally on the said yoke against the action of the governor balls, a plunger, a spring tending to force the plunger against said lever, a latch resisting the tendency of the plunger spring, a trigger controlling said latch, and a belt pulley mounted on said trigger.

4. In a governor the combination with a governor yoke and a belt pulley secured thereto, of a pivoted lever, a spring exerting pressure on said lever to hold the arm normally on the yoke against the action of the governor balls, a plunger, a spring tending to force said plunger against said lever, a latch resisting the tendency of the plunger spring, a trigger controlling said latch, a belt pulley on said trigger, and a belt on the pulley on the said head against which the trigger pulley bears.

5. In a governor for engines the combination with the governor yoke, of a frame, a lever pivotally mounted on said frame, a bracket, a spring seated on said bracket and exerting pressure against said lever to hold the lever on the yoke against the action of the governor balls, a plunger mounted on said bracket, a spring tending to force said plunger against said lever, a latch pivoted to said frame resisting the tendency of the plunger spring, a trigger controlling said latch, and a belt pulley carried by said trigger.

6. In a governor, the combination with the governor mounting of an arm extending therefrom, a bracket secured to said arm, a spring impelled plunger mounted on said bracket, a frame secured to the governor mounting, a bell crank lever pivotally mounted on said mounting, one end of which is detachably connected to the governor frame, a spring secured to said bracket and exerting pressure against said bell crank lever to hold it normally in engage-

ment with the governor frame, a latch pivotally secured to the mounting constructed to engage said plunger and hold it against the action of its spring, a trigger to control said latch and a belt idler pulley mounted on said trigger.

The foregoing specification signed at Oil

City, Pennsylvania, this 23rd day of Sept.
1912.

WILBER O. PLATT.

In presence of two witnesses—

J. S. TRAX,

A. S. TURNER.
